UNITED STATES PATENT OFFICE.

ALEXANDER F. FROMHOLD, OF NEW YORK, N. Y., ASSIGNOR TO S. H. POMEROY COMPANY, INC., OF NEW YORK, N. Y., A CORPORATION OF NEW YORK.

METAL WINDOW FRAME.

Application filed January 2, 1923. Serial No. 610,101.

To all whom it may concern:

Be it known that I, ALEXANDER F. FROMHOLD, a citizen of the United States, and a resident of the borough of Manhattan, of the city of New York, in the State of New York, have invented certain new and useful Improvements in Metal Window Frames, of which the following is a specification, reference being had to the accompanying drawing, forming a part hereof.

This invention is concerned particularly with the construction of the hollow metal jambs or vertical side members of a window frame, between which the sashes slide. It has for its objects to reduce the cost of construction, to avoid the necessity of employing a great number of screws or bolts to secure the parts together without sacrificing rigidity and tightness, and to make the window more certainly weatherproof. The invention will be more fully explained hereinafter with reference to the accompanying drawing in which it is illustrated as embodied in a suitable structure and in which—

Figure 1 is a view in elevation, partly in vertical section, of a portion of a window frame which embodies the invention, a portion of one of the sashes being also shown.

Figure 2 is a view in horizontal section on the plane indicated by the line 2—2 of Figure 1.

Figure 3 is a view in elevation as seen from the right hand in Figure 1, partly broken out.

Each hollow jamb or vertical side member, which also constitutes the weight box, comprises a pulley-stile *a* and the main body of the jamb, which may be formed of two parts *b* and *c*, united by a folded seam, as at *d*. The parts *b* and *c* of the jamb are suitably formed to fit the masonry of the window opening, and the face portion *b'*, *c'* of each, at right angles to the planes of the window sashes *e*, is bent inward at an acute angle, as at *b²*, *c²*, is then bent at an acute angle into a plane parallel with the face, as at *b³*, *c³*, and is then bent into a curve as at *b⁴*, *c⁴*, slightly more than a quarter-round. The pulley-stile *a* has a flat face *a'* of a width which corresponds to the difference between the planes of the upper and lower sashes, approaching closely enough, at the angles *a²*, to the angles *b⁵* and *c⁵* formed by the parts *b'*, *b²* and *c'*, *c²*, to afford a fairly snug sliding fit for the projecting web *e'* of

the corresponding sash *e*. It is then bent inwardly at an acute angle, as at *a³*, is again bent at an acute angle into parallelism with the face, as at *a⁴*, and is then bent into a half-round, as at *a⁵* to bear against the extended quarter-rounds *b⁴* and *c⁴* above mentioned and to form a bearing or line of sliding contact for the web *e'* of the corresponding sash.

Heavy metal braces *f*, distributed at suitable intervals in the height of the jamb, and arranged to bear against the curved portions *b⁴* and *c⁴* above mentioned, are engaged by screws *g*, which are passed through the face *a* of the pulley-stile, between the planes of the sashes, into the central portions *f'* of the braces, which central portions stand between the angles of the parts *a³* and prevent the collapsing of the central portion of the jamb or the pulley-stile. The braces are further extended and bent, as at *f²*, parallel with the sides *b²* and *c²* and again, as at *f³*, parallel with the faces *b'* and *c'* of the jamb, and the ends of the braces preferably bearing against the front and rear walls of the jamb. The braces thus support and stiffen and prevent the collapsing of the jamb and thus prevent the use of a relatively light gauge of metal in the construction of the jamb without sacrificing the desired stiffness and rigidity.

It will be observed that when the screws *g* are set up, since the braces bear against the free overlapping portions of the main members of the jamb and of the pulley-stile and at their middle points are spaced from the face of the pulley-stile, they draw the braces *f* tightly against the curved portions *b⁴* and *c⁴* and these curved portions against the curved portions *a⁵* of the pulley-stile, thereby insuring a tight closure of the joint which is formed at these points and so preventing the access of moisture to the inside of the weight box. Furthermore, the curved portions *a⁵* are drawn toward the sashes so that a close sliding fit between the webs of the sashes and the curved portions *a⁵* is assured and a weather-tight joint is thus formed with the webs of the sashes as well as the weather-tight joints between the angle *b⁵* and the upper sash and the angle *a²* and the lower sash. The double weather-proof joint thus formed effectually prevents the entrance of cold air and moisture into the room at the sides of the sashes. Each of the sashes, at each side, is connected by a

link e^2 and a chain h , which passes over the usual pulley h' , to the corresponding sash weight h^2 . It will be observed that the curved parts a^5, b^4, c^4 can easily be closed or opened more or less in each instance as may be desirable to secure the proper contact. It will further be noted that all parts are rigidly secured together by the screws which stand in a vertical series between the planes 10 of the sashes and that no screws are required at the outside or the inside portions of the jamb.

I claim as my invention:

1. A metal window jamb having a main 15 jamb member bent inward from its face with a curved portion at its edge, a pulley-stile also bent inward from its face with a curved portion at its edge overlapped by the curved portion of the main jamb member 20 and interlocking therewith and forming a guide groove for the sash, and means to secure the parts together.

2. A metal window jamb having a main jamb member bent inward from its face

with a curved portion at its edge, a pulley- 25 stile also bent inward from its face with a curved portion at its edge overlapped by the curved portion of the main jamb member and interlocking therewith and forming a guide groove for the sash, a heavy metal 30 brace bearing against the overlapping portions, and a screw passed through the pulley-stile into the brace to secure the parts together.

3. A metal window jamb having a main 35 jamb member bent inward from its face at an acute angle and bent at an opposite acute angle with a curved portion at its edge, a pulley-stile also bent inward from its face at an acute angle, and again at an acute 40 angle with a curved portion at its edge overlapped by the curved portion of the main jamb member and interlocking therewith and forming a guide groove for the sash, and means to secure the parts together. 45

This specification signed this 29th day of December A. D. 1922.

ALEXANDER F. FROMHOLD.
